Primary Examiner — Sheryl Lane*Assistant Examiner* — Mark T. Philipp(74) *Attorney, Agent, or Firm* — Fitch, Even, Tabin & Flannery LLP(57) **CLAIM**

I claim the ornamental design for a rolled material dispensing apparatus, as shown and described.

DESCRIPTION

FIG. 1 is a front-top perspective view of a rolled material dispensing apparatus showing my new design;

FIG. 2 is a bottom-rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof; and,

FIG. 8 is a bottom view thereof.

The broken lines show portions of the rolled material dispensing apparatus that form no part of the claimed design.
